VOLTAGE-LIMITING ARC INTERRUPTER

Ralph R. Pittman, Little Rock, Ark.

Application March 7, 1944, Serial No. 525,465

2 Claims. (Cl. 175—30)

1

This invention relates generally to discharge device constructions for the purpose of limiting the rise in voltage, such as might be caused by lightning or switching surges, of a connected conductor by means of arcing gaps adapted to breakdown at a predetermined voltage, together with means for quickly interrupting the passage of current through the arcs attending break down of the gaps.

It has been generally recognized that arcing gaps of the self-extinguishing type offer the best means now known for dissipating extraneous or superimposed high voltages which appear in electric circuits. Such devices utilize gas evolved by the heat of the arc to cause its extinction. The gas and flame discharged from constructions now available is highly conducting, and this consideration has in many situations prevented the use of this otherwise desirable character of protection, for the reason that the discharged conducting gas may bridge contiguous live parts and thereby cause serious damage to equipment. So far as applicant has been able to discover, no construction is now available for satisfactorily enclosing gas-evolving arcing-gap mechanisms, so that no gas or flame is discharged when operating.

Among the objects of the present invention may be noted the provision of means for completely enclosing a voltage-limiting device of the gas-discharge type without adversely affecting the protective qualities or useful life of the device; the provision of an enclosed arc interrupter in which the space within an insulating housing is efficiently utilized to provide a small and inexpensive construction; the provision of an arrangement for confining and quickly cooling the incandescent gases evolved; and the provision of a simple structure in which several of the component elements perform two or more necessary or desirable functions. Other objects will be in part obvious, and in part pointed out herein-after.

The invention comprises the elements and combinations thereof, features of construction, and arrangement of parts to be exemplified in the description to follow, and the scope of the invention will be indicated in the accompanying claims.

In the drawings: Fig. 1 is a sectional view illustrating the construction of one complete device; and Fig. 2 illustrates a series arrangement of several of the devices, for application to circuits higher in voltage than that for which a single device may be suitable.

Similar reference characters indicate corre-

sponding parts in the several figures of the drawing.

Referring in detail to the drawing, an upstanding hollow cylindrical housing of insulating material, 10, is provided at its respective ends with the outwardly extending peripheral flanges 13 and 14, which may be conveniently secured to the housing 10 by cementing. An upper closure of conducting material 11 is fitted over the upper end of the housing 10, and rigidly secured thereto by the flange bolts 15. Similarly, a lower closure of conducting material 12 is rigidly secured at the lower end of the housing 10 by means of the flange bolts 16. The upper closure 11 is provided with the upper or line terminal 17, and the lower or ground terminal 18 is mounted on the conducting supporting base 34.

A dividing wall or partition of conducting material 19 is supported within the housing 10 from an outwardly turned flange at the lower end of the partition, the latter being clamped between the flange 14 and the lower closure 12; the partition 19 extending upwardly along and in spaced relationship with the inside of the housing 10. Along a horizontal plane substantially below the upper closure 11, the partition 19 is extended inwardly and thence downwardly, terminating at an inwardly-turned integral flange within the lower portion of the housing 10. In this manner the partition 19 divides the space within the housing 10 into two parts, namely, the spark-gap chamber 20, and the exhaust chamber 21.

The voltage-responsive arc-quenching device 22 is mounted, in spaced relationship with both the closures 11 and 12, on the inwardly-turned flange of the partition 19, by means of the mounting screws 29, the latter extending upwardly through the outwardly extending flange of the lower conducting electrode 25 of the discharge device 22.

As illustrated, the discharge device 22 is similar to, and described more in detail, in U. S. Patent No. 2,164,720, dated July 4, 1939, and issued to Ralph R. Pittman. Such a device is suitable for use in the present invention, but it will also be apparent that other voltage-responsive arc-quenching construction might be used.

As shown in Fig. 1, the discharge device 22 includes the upstanding tubular insulator 23, and has secured thereto by means of threaded engagement at its respective ends, the upper conducting electrode 24 and the lower conducting electrode 25. The tubular insulator 23 contains the eccentrically mounted filler 27, also of insulating material. The lower electrode 25 is provided with the upwardly and internally extend-

ing extension 26, the arrangement being such that the weakest electrical path through the device is along the line of abutment of the filler 27 with the inner surface of the tubular insulator 23, and between the upper end of the electrode extension 26 and the upper electrode 24. Following spark-over of the weakest electrical path, any arc ensuing is driven around the filler 27, being concurrently moved laterally and elongated, and so cooled to facilitate extinguishment. The openings 28 through the lower electrode 25 vent the gaseous products attending the arc, and the device is economically constructed when the tubular insulator 23 and the filler 27 are formed of arc-responsive gas-evolving material, such as hard fiber.

The upper electrode 24 is preferably spaced from the lower surface of the upper conducting closure 11 to form the spark gap 33, so that under normal conditions the tubular insulator 23 is not subjected to voltage stress.

To facilitate cooling of the incandescent gas discharged when the discharge device 22 operates, a discharge disperser or distributor 30, formed as a cup provided with a large number of small perforations 31, is fitted over the vented end of the insulator 23, being held in position by the means of the mounting screw 32. Preferably the disperser is constructed of a material of good heat conductivity, such as copper, and the thickness of the wall is of the order of three-eighths of one inch, so that the temperature of the gas discharged therefrom is substantially reduced before reaching the exhaust chamber 21.

The conducting members embodied in the construction are so coordinated with the insulating members that the weakest electrical path from the upper terminal 17 to the lower terminal 18 is from the upper terminal 17 to the upper conducting closure 11, thence across the spark gap 33 to the upper electrode 24, thence within the tubular insulator 23 to the lower electrode extension 26, thence to the lower electrode 25, thence through the conducting dividing wall 19 to the lower closure 12, and thence through the conducting base 34 to the lower terminal 18.

The partition 19 prevents contamination of the inner surface of the insulating housing 10 and the outer surface of the tubular insulator 23, which would occur if the gas discharged from the discharge device 22 contacted the surfaces. A certain amount of incandescent-free carbon is often expelled from the discharge device, which, when deposited on the surface of an insulator, provides a conducting layer. In addition to shielding the insulating surfaces from contamination, the partition 19 also provides a support for the discharge device, and is so arranged that the inherent resiliency of the metal from which the partition is formed absorbs the impact attending the operation of the discharge device. A further function of the partition 19 is to provide conducting means for connecting the lower electrode 25 to the lower conducting closure 12 and the lower or ground terminal 19.

In certain situations, it may be economical to construct the interrupter in units suitable for a definite voltage rating, stacking the units in series circuit relation for use on higher voltage circuits. Fig. 2 illustrates such a stacked arrangement, showing three units which are connected in series simply by bolting the lower closure of one unit to the upper closure of another. Considerable economy results from the construction of the individual units for about 11 kv. op-

eration; the stacked arrangement illustrated would, under this condition, be suitable for application to a 33 kv. circuit.

It is intended that the description presented herein will be regarded as illustrative of the invention, rather than limiting.

I claim:

1. A voltage-limiting arc interrupter comprising a hollow cylindrical housing of insulating material having upper and lower closures of conducting material at its respective ends; a re-entrant partition of conducting material extending within said housing, said partition engaging the lower closure and extending first inwardly and upwardly from the lower end of said housing to an elevation below that of the upper closure, thence inwardly and downwardly to a centrally positioned opening at an elevation above that of said lower closure; a discharge device including an upstanding tubular insulator closed at the upper end and vented at the lower end, normally insulated spaced upper and lower conducting electrodes associated therewith and so related that the weakest electrical path therebetween is within said insulator rather than externally thereof; means supporting said discharge device on said partition at said last-named elevation, said discharge device extending upwardly in lateral spaced relationship with said partition and in vertical spaced relationship to the upper closure to provide a spark gap between the latter and the upper electrode of said discharge device, the lower end of said discharge device closing said centrally positioned opening and being arranged to vent gaseous products attending the operation of said discharge device only into the space between said lower closure and said reentrant partition; and a discharge disperser mounted at the vented end of said discharge device for cooling said gaseous products prior to entry into said space; the conducting members being so related to the insulating housing that the weakest electrical path from said upper closure to said lower closure is via the series circuit arrangement of said spark gap and said discharge device.

2. A voltage-limiting arc interrupter comprising a hollow cylindrical housing of insulating material having upper and lower closures of conducting material at its respective ends; a re-entrant partition of conducting material extending within said housing, said partition engaging the lower closure and extending first inwardly and thence upwardly along and spaced from the inner surface of said housing, thence inwardly toward and spaced from the axis of said housing, and thence downwardly to an opening therein at an elevation above that of said lower closure; a discharge device including an upstanding tubular insulator closed at the upper end and vented at the lower end, normally insulated spaced upper and lower conducting electrodes associated therewith and so related that the weakest electrical path therebetween is within said insulator rather than externally thereof; means supporting said discharge device on said partition at said last-named elevation, said discharge device extending upwardly in lateral spaced relationship with said partition and in vertical spaced relationship to the upper closure to provide a spark gap between the latter and the upper electrode of said discharge device, the lower end of said discharge device closing the opening in said partition and being arranged to vent gaseous products attending the operation of said discharge device only into the space between said lower closure and said

reentrant partition; and a discharge disperser mounted at the vented end of said discharge device for cooling the gaseous products prior to entry into said space; the conducting members being so related to the insulating housing that the weakest electrical path from said upper closure to said lower closure is via the series circuit arrangement of said spark gap and said discharge device.
